UNITED STATES PATENT OFFICE.

SAHN K. LOWE, OF SAN FRANCISCO, CALIFORNIA.

PULVERIZING MACHINE.

Application filed December 15, 1923. Serial No. 680,974.

To all whom it may concern:

Be it known that I, SAHN K. LOWE, a citizen of the United States, and a resident of San Francisco, county of San Francisco,

5 State of California, have invented a new and useful Pulverizing Machine, of which the following is a specification.

This invention relates to machines as used for pulverizing various materials and particularly to such machines as are adapted to pulverize fibrous materials which cannot be reduced to the necessary fineness by attrition or ordinary grinding but require definite cutting as well.

10 The particular objects of my invention are to produce a simple structure which will receive the raw material and discharge it as an impalpable powder without requiring any intermediate or subsequent grindings, and a device wherein the feed can easily be regulated from the outside, and which will permit of quick and easy interchange of sizing elements so that the size of the finished particles may be varied with certainty, a 15 device providing a plurality of shearing edges associated with attrition surfaces so as to effectually handle fibrous materials, means for maintaining the pressure of the attrition surfaces and the operative relation 20 of the shearing edges, means for causing a constant flow of the material being treated over the sizing elements to the reducing elements and return in recurring cycles with a continuous separation of the finally reduced 25 particles and ejection from a common outlet, means of lubricating the bearings of the internal reducing elements effectually sealing them against ingress of reduced material or against contamination of the product with 30 oil, a balanced rotary device consuming a low percentage of energy, an assemblage providing for easy resharpening or changing of the cutting elements, and one which is easily disassembled for general cleaning 35 and overhauling.

I attain the objects enumerated together with other constructional advantages in the arrangement of elements shown in the accompanying drawings and in which:—

40 Figure 1 is a view in elevation of the apparatus partly in section and with portions broken away revealing the interior; Figure 2 is a plan section of a portion of the apparatus taken along the line 2—2 of Figure 45 1; and Figure 3 is an elevation of the central feed cup and associated feed regula-

tion device as seen from the line 3—3 of Figure 1, and it also shows the chopping blade. Figure 4 shows, enlarged, the cutter and groove relation.

60 In the drawings, (1) represents a stationary round base member supported on legs (2) and provided with a central vertical bearing hub (3).

The base member has an upwardly extending flange (4) having a series of openings (5) formed in it, and supports on its upper edge a concentric cylindrical portion (6) held in place preferably by means of bayonet locking pins (7).

65 On top of the cylindrical portion (6) is a similar section (8) similarly held by the locks (9), and above section (8) is a lid (10) having a handle (11) and air vents (12). At the lower edge of section (8) is secured 70 a funnel shaped bottom (13) terminating in a central feeding cup (14), the arrangement being such that the section (8) being filled with material to be treated will deliver 75 it over the funnel bottom to the feeding cup.

80 Below the cup is a revolving bowl (15) supported on a thrust bearing or washer (16) resting on the upper end of hub (3) and secured to a vertical shaft (17) revolvable in the hub (3) and to which shaft power 85 may be applied by any suitable means not shown. Above the center of the bowl is a revolvable feeding block (18) being formed with a lower flange (19) with a depending stem (20) threaded into the upper end of 90 the shaft. The block (18) is revolved by the shaft for the purpose of forcing material from the feeding cup (14) against a 95 chopping blade (21) fixed on the cup and having its edge directed through a slot (22) and adjacent the inner circumference of the cup as shown best in Figure 2.

100 While the drawing shows but one cutter and one revolving block, it is apparent that any number may be used.

The bowl (15) has arms (15') connecting an upwardly slanted edge (15^a) supporting a grooved steel ring (23) suitably secured to it for combined rotation, and under the arms is a circular disk or pan (24) secured to the bowl and having a plurality of short vanes (25) spaced around its outer edge and suitably fastened to the disk and to the upper flange (15^a) of the bowl.

110 The object of the vanes is to cause a current of air and material to be thrown outwardly upon the revolution of the bowl

so that the finished material will all be drawn toward and forced out of a common outlet (26) which preferably communicates with a slot extending some distance about 5 the circumference of the base member (4).

Above the bowl is supported a disk shaped screen frame (27). This screen frame rests lightly on the bowl along its outer edge and at its center engages an eccentric hub (28) formed on the upper end of the shaft.

The screen is stopped from revolving by an arm or arms (29) extending from the stationary section (6) of the apparatus and engaging an edge of a lug (30) turned upward on the rim of the screen frame, and whereby the eccentric hub is revolving with the shaft causes a gyratory or oscillating vibration to the screen, which, together with the outward air currents causes a constant 15 outward flow of particles delivered to the screen from the chopping blade (21).

The material passes over the outer edge of the screen to the slanted edge (15²) of the bowl where by centrifugal force it is thrown 25 into the groove (31) of the ring (23). Revolving in engagement with the groove of the ring are grinding and cutting disks (32) revolvably supported on arms (33) hinged at (34) to the member (6) and spring actuated as indicated at (35) to keep 30 the disks in constant yielding pressure contact with the ring.

These cutter disks have tapered edges to match the tapered groove as shown and are further provided with annular grooves (36) to cooperate with a similar series of grooves (37) in the upper side of the groove of the ring to form a series of shearing edges.

The lower edge of the cutters also has a shearing action against the lower edge of the groove, and the tapered form of the cutters and groove, on account of the larger diameter of the latter; form rotary 40 wedging attrition surfaces between which the material is rubbed out, as it were, into an impalpable powder.

On top of the ring (23) is a light sealing flange (38) to close the space between the outer edge of the bowl and the member (4), the sealing flange resting lightly upon the upper edge of the latter member.

Fitted within the member (4) is a very fine collar shaped screen ring (39) to provide additional means for the escape of the air through the frame openings (5) yet prevent the passage of powdered material.

In operation the ground material accumulates in the groove of the ring and also on the upper surface of the sealing flange (38) and is removed by suitable scrapers secured to the member (6) and bearing against the groove and flange as indicated at (40). The scrapers are formed to return the material centrally of the machine for repas-

sage over the screen and again over the grinding elements.

The cutters (32) are recessed on the upper side as shown and embrace two ball cones (41) and (42), the latter having a stem 70 threaded through the former and passing through the arm clamped thereto by the nut (43). The stem is drilled for oiling the bearing and provided with a spring closure (44).

A row of balls (45) is arranged between the inner edge of the recess of the cutter and the cones as shown and the cones after proper adjustment are locked against movement by clamping both to the arm with the 80 nut.

Over the recess in the cutters is a tightly fitting cover plate (46) and above that a felt washer (47). It will thus be seen that once the cutters are adjusted and oiled they remain in adjusted condition, cannot be clogged by powdered material nor contaminate the same with oil.

The arrangement of the cutters on the hinged arms in relation to the ring is shown 90 in Figure 2 and this figure also shows the setting of the chopping blade (21) in relation to the cup (14) and the revolvable feeding block (18).

Figure 3 shows the cup in elevation and with a sliding plate (48) fitting the groove in the cap in front of the knife edge for adjustably exposing any desired length of edge for cutting the raw material. The plate (48) has a slotted flange lying against 100 the cup and slidably secured thereto by a rivet (49), and is raised or lowered by a screw (50) (here shown broken off) passing through a lug (51) on the plate.

The adjustment of the plate is accomplished from the outside of the apparatus while in motion if desired.

Figure 1 shows the manner of adjusting the slide, the screw (50) has bearing in a lug (52) at the juncture of the funnel and cup and has a bevel gear (53) secured to its upper end meshing another gear (54) secured to a shaft (55) passing out of the apparatus with a device (56) on the outer end for turning it.

By the arrangement just described it will be evident that the slide can be worked to expose any amount of the edge of the chopping blade or none at all, and thereby positively controlling the feed of particles cut from the raw material and fed to the reducing and sizing elements described.

Having thus described my improved pulverizer it will be seen to effect the objects outlined, and while I show specific features in order to attain these objects it is understood that any such modifications as come within the spirit of my invention are intended to be covered in the appended claims.

I claim:

1. In a pulverizing machine, a horizontally revolvable disk, means for feeding material to the center of the disk, openings through the disk and a screen over the 5 openings, means at the central portion of the disk for cutting the material and for passing it outwardly across the screen, means beyond the screen for further cutting and grinding of the material and means for 10 returning it to the same screen for a repetition of the treatment.
2. In a pulverizing machine, a horizontally revolvable disk, means for feeding material to the center of the disk, openings 15 through the disk and a screen over the openings, means at the central portion of the disk for cutting the material and for passing it outwardly across the screen, means beyond the screen for further cutting 20 and grinding of the material, means for returning it to the same screen for a repetition of the treatment, and means revolvable with the disk for conveying the 25 screened material peripherally to an outlet from the machine.
3. In a pulverizing machine of the class described, reducing elements comprising a circular revolving body with a tapered groove therearound and a circular cutter 30 having a blade adapted to mesh with said groove supported to revolve in yielding contact with the groove.
4. In a pulverizing machine of the class described, reducing elements comprising a circular revolving body with a tapered groove therearound and a circular cutter having a blade adapted to mesh with said groove, a hinged arm supporting the cutter to revolve in mesh with the groove, and 40 means for resiliently acting against the arm for holding the cutter against the revolving body.
5. In a pulverizer of the character described, a horizontally revolvable disk for 45 receiving the material centrally and throwing it outwardly, openings through the disk and a screen thereover, a spaced pan under and secured to the disk, and vanes between the pan and the disk for causing an air current through the screen upon the revolution of the disk.
6. In a pulverizer of the character described, a horizontally revolvable bowl shaped disk for receiving the material centrally and throwing it outwardly, openings 55 through the disk and a screen thereover, a spaced pan under and secured to the disk, vanes between the pan and the disk for causing an air current through the screen upon the revolution of the disk, a ring secured to the edge of the bowl shaped disk and having a groove around its inner edge, a plurality of revolvable reducing elements 60 mounted in engagement with the groove for reducing the outwardly thrown material,
- and means for removing adhering material from the ring and dropping it on the screen.
7. A pulverizer of the character described comprising a cylindrical receptacle, a revolving disk within and spaced from the 70 bottom thereof, a screen on the disk, means for feeding material to the center of the disk, means at the central portion of the disk for cutting the material and feeding it to the screen, openings in the disk below 75 the screen, and means for creating an air current downward through the screen.
8. A pulverizer of the character described comprising a cylindrical receptacle, a revolving disk within and spaced from the 80 bottom thereof, a screen on the disk, means for feeding material to the center of the disk, means at the central portion of the disk for cutting the material and feeding it to the screen, and vanes on the under side of 85 the disk for creating an air circulation through the screen upon revolving the disk.
9. In a pulverizer of the character described, a horizontally arranged perforated 90 revolvable disk for feeding centrally deposited material outwardly, a screen over said disk held against rotation, and means actuated upon revolving the disk for shaking said screen.
10. In a pulverizer of the character described a horizontally revolvable disk, a feeding cup held centrally above the disk, a slot through the side of the cup, a cutter secured to the cup projecting inwardly 95 through the slot, means on the disk within the cup for forcing material over the cutting edge of the cutter, and means for varying the length of the slot for controlling the exposed cutting edge of the cutter. 100
11. In a pulverizer of the character described, a horizontally revolvable disk, a feeding cup held centrally above the disk, a slot through the side of the cup, a cutter secured to the cup projecting inwardly 105 through the slot, means on the disk within the cup for forcing material over the cutting edge of the cutter, and means for varying the length of the slot for controlling the exposed cutting edge of the cutter, said latter 110 means comprising a sliding block in the slot operated by a handle accessible from without the pulverizer.
12. In a pulverizer of the character described, a plurality of removably interlocked cylindrical sections including an upper vented section and a lower supporting section, a hopper bottom within one section for depositing material centrally downward, a revolvable disk under the hopper section for receiving the material centrally, successive reducing elements, respectively, at the hopper and at the edge of the disk, a shaker screen through which the reduced material passes, means for shaking 120 the screen, means for creating an air cur- 125
- 130

rent to aid the flow of material, and a discharge for screened material at the edge of the lower section.

13. In a machine of the character described, a revolvable cutter comprising a recessed shell having an inner ball race therearound, a pair of cones within the shell and a row of balls in the race around the edges of the cones, one of said cones having a central opening and the other provided with a stem threaded through the opening for adjusting the cones and for clamping to a support.

14. In a machine of the character described, a revolvable cutter comprising a shell recessed from one side only and having an inner ball race therearound, a pair of cones within the recess and a row of balls in the race around the edges of the cones, one of the cones having a central opening and the other a stem extending through the opening for clamping to a support, and a dust cover surrounding the stem over the recess.

15. In a pulverizer of the character described, a revolvable member having an internal tapered groove, and a similarly tapered revolvable disk seated in the groove, the tapered sides of the groove and cutter being similarly stepped or grooved to form cooperating concentric shearing edges.

16. In a pulverizing machine, a central feeding cup for the raw material, means adjacent the cup for reducing the material from the cup and discharging it therefrom, means for moving the material outwardly

from the cup, and means around the cup for further reducing the material, said means comprising a revolvable ring and a roller rolling against said ring.

17. In a pulverizing machine, a central feeding cup for the raw material, means adjacent the cup for reducing the material from the cup and discharging it therefrom, means for moving the material outwardly from the cup, and means around the cup for further reducing the material, said means comprising a revolvable ring and a revolvable cutter bearing against the ring.

18. In a pulverizing machine, a central feeding cup for the raw material, means adjacent the cup for reducing the material from the cup and discharging it therefrom, means for moving the material outwardly from the cup, and means around the cup for further reducing the material, said means comprising a revolvable ring with a groove therein, and a revolvable cutter meshing with the groove.

19. In a pulverizing machine, a central feeding cup for the raw material, means adjacent the cup for reducing the material from the cup and discharging it therefrom, means for moving the material outwardly from the cup, and means around the cup for further reducing the material, said means comprising a revolvable ring with a taper groove therein and a plurality of revolvable cutters having tapered edges meshing with the groove.

SAHN K. LOWE.
